INVENTOR.

Sam Ford,

BY

Geo. F. Kimmel.

ATTORNEY.

UNITED STATES PATENT OFFICE.

SAM FORD, OF TOLEDO, OHIO.

COMBINED BED AND WARDROBE.

Original application filed August 5, 1927, Serial No. 210,876. Divided and this application filed February 7, 1928. Serial No. 252,594.

This invention relates to an article of furniture, such as a bed, more particularly to a combined bed, wardrobe and trunk, and is a division of my application filed August 5, 1927, Serial No. 210,876, and has for its object to provide, in a manner as herein-after set forth a unit including a bed and a wardrobe and with the wardrobe constituting the foot element of the bed and where- 10 by the unit will occupy a minimum space substantially the same as that occupied by an ordinary bed.

A further object of the invention is to provide, in a manner as herein-after set forth, 15 an article of furniture in the form of a single unit functioning as a bed and a normally closed wardrobe and with the unit including means to provide for conveniently opening the wardrobe when desired.

20 A further object of the invention is to provide, in a manner as herein-after set forth, an article of furniture in the form of a unit and functioning as a bed and a normally closed wardrobe formed with a vertically 25 shiftable sliding door.

Further objects of the invention are to provide, in a manner as herein-after set forth, 30 an article of furniture in the form of a single unit comprising a bed and a wardrobe and with the unit comparatively simple in its construction and arrangement, strong, durable, compact, thoroughly efficient in its use, not impairing the appearance of the room in which the unit is used, readily assembled, conveniently disassembled when required, and comparatively inexpensive to manufacture.

With the foregoing and other objects in view the invention consists of the novel construction, combination and arrangement of parts as herein-after more specifically described, and illustrated in the accompanying drawings, wherein is shown an embodiment of the invention, but it is to be understood 45 that changes, variations and modifications can be resorted to which fall within the scope of the claims hereunto appended.

In the drawings wherein like reference characters denote corresponding parts throughout the several views:

Figure 1 illustrates in side elevation, an article of furniture in accordance with this invention.

Figure 2 is a fragmentary view in front 55 elevation of the foot element of the unit and

further illustrating said element partly open. Figure 3 is a fragmentary view in vertical section of the unit, and further illustrating the wardrobe forming a part of the foot element closed.

60 Figure 4 is a fragmentary view partly in section and in front elevation of the foot element.

Figure 5 is a sectional plan of the foot element.

65 Figure 6 is a fragmentary view in longitudinal section of the upper portion of the foot element.

Figure 7 is a fragmentary detail in vertical section illustrating a bearing for the 70 closure for the wardrobe forming a part of the foot element.

Figure 8 is a fragmentary view in elevation of the foot element.

Figure 9 is a section on line 9-9 Figure 5. 75

An article of furniture in the form of a unit and in accordance with this invention is a combined bed, wardrobe, trunk and storage compartment and said unit includes a pair of side rails A, B, a head element C 80 and a foot element D. The side rails A, B, detachably connect with the elements C and D for not only coupling them together but for maintaining them in spaced relation. The head element C is of greater height than 85 the foot element D although it is to be understood that the elements C and D can be constructed of any desired height.

As the side rails A and B are of like construction, but one will be described, as the 90 description of one will apply to the other.

The side rails are oppositely disposed with respect to each other and are of angle shaped cross section and each side rail comprises a vertically disposed portion 1 and a horizontally disposed portion 2 and with the latter extending inwardly at right angles with respect to the bottom of the former. Secured to the inner face of the vertical portion 1, in proximity to each end thereof, and extending down through the horizontal portion 2, as well as projecting a substantial distance therebelow, is a vertically disposed coupling pin 3, which has its upper portion fixedly secured to the inner face of the vertical portion 1 of the rail. The vertical portion 1 of each of the rails, has projecting 95 from its outer face, in proximity to each end thereof, a headed coupling lug 4. The pins 3 and lugs 4 coact with the elements C and D. 100

105 Figure 1 illustrates in side elevation, an article of furniture in accordance with this invention.

Figure 2 is a fragmentary view in front 110 elevation of the foot element of the unit and

for the purpose of detachably connecting the side rails therewith, whereby the elements C and D will be coupled together and maintained in spaced relation and the manner in which the said pins and lugs associate with said elements C and D will be presently referred to. The side rails can be of any appropriate length desired and any suitable cross sectional area. When the side rails are mounted in position relative to the elements C and D, they abut the inner faces of said elements, in a manner as shown in Figure 3.

The foot element includes a pair of posts or standards 46, 47 preferably of less height than the element C, but it is to be understood that the height of the posts 46, 47 can be as desired. The inner side of the post 46, as well as the post 47, is cut away to provide in proximity to the upper end of the post a shoulder 48 and further to provide a shoulder 49. Secured to and arranged between the posts 46, 47 in proximity to their upper ends is a horizontally disposed, flat combined brace and connecting member 50 having its side edges flush with the front and rear edges of the posts, and secured between the posts 46, 47 at a point an appropriate distance above the lower ends thereof is a combined brace and supporting member 51, which is positioned on edge and is flush with the rear edges or faces of the posts 46, 47.

Arranged between the posts 46, 47 and extending from the member 50 to the member 51 as well as abutting against the post 47 is a wall forming member 52. Secured to the post 46, between the shoulders 48, 49 thereof and projecting outwardly therefrom is a wall forming member 53. Secured between the shoulders 48, 49 of the post 47 and projecting outwardly therefrom is a wall forming member 54, which opposes the member 53. Secured between the posts 46, 47 and upon the upper ends of the members 43, 44 is a top wall forming member 55. The members 53, 54 and 55 abut against the member 52 and secured between the members 53, 54 above the lower ends thereof, and abutting against the member 52, is a horizontally disposed bottom forming member 56. The members 52 to 56 inclusive provide a wardrobe having an open outer side and with such side normally closed by a vertically shiftable door 57. The members 53, 54 depend below the member 56 and the door 57 slides below said member 56.

Secured to the inner face of the member 53, as well as the member 54, is a pair of spaced guide rails 57', 58 each provided with a plurality of roller bearings 59 and between the roller bearings slides the flexible door 57. The members 53, 54, below the member 56, are connected together by a combined brace and coupling member 60, which is disposed at an inclination and constitutes a guide for the closure or door 57. Projecting rear-

wardly from the member 60 as well as being secured to the bottom thereof, are spaced guides 61 having curved upper faces as indicated at 62. The member 60 and guides 61 also provide deflectors to cause the closure 57 or door 57 to move to the dotted line position shown in Figure 3 when the door 57 is shifted downwardly to open the wardrobe. The door or closure 57 is provided with a handle member 63 and a hook 64. The member 55 carries a resilient latch 65 which coacts with the hook 64 for maintaining the door or closure 57 in closed position with respect to the wardrobe. The door or closure 57 is overlapped by the guide rails 58 see Figure 2.

Secured to the lower face of the top wall forming member 55 is a pair of oppositely disposed spaced tracks 66 and roller bearings 67 are carried by each of the tracks. Slidably mounted in the tracks 66 is a suspension member 68 in the form of a skeleton frame and which includes transversely extending bars 69 providing suspension means for clothes hangers 70. The suspension member 68 can be moved inwardly and outwardly with respect to the tracks 66. Secured to the lower portion of the inner face of the wall forming member 52 is a hat holder 71.

The post 46, as well as the post 47, is provided with a pair of socket forming members 72, 73, the former being arranged above the latter and which is adapted to receive a headed stud 4. A pin 3 is adapted to engage in the socket forming member 73 inwardly with respect to the socket forming member 72. The socket forming members 72 and 73, carried by the posts 46, 47 provide means for detachably connecting the side rails to the foot element D. Socket forming members 72', 73' are carried by each of the posts of the head element C and are constructed similar to the members 72, 73. The sockets formed by the members 72, 72' are disposed at right angles to the sockets formed by the members 73, 73'. The members 72', 73' in connection with headed studs 4 and pins 3 provide for coupling the side rails to the head element C. The posts of the head element C have castors 75.

The outer guides 62 are braced from the posts 46, 47, as at 74. The post 46 as well as the post 47 is provided with a castor 75.

The bottom wall forming member 56, which forms a part of the foot element D, is of less width than the width of a wall forming member 53 or 54 and the guide rail 57' extends from the member 56 to the member 55. The guide rail 58 extends from the member 55 to a point a substantial distance below the member 56, and is spaced forwardly of the latter.

It is thought the many advantages of an article of furniture in the form of a unit

and functioning as a bed, wardrobe, trunk and a storage compartment, can be readily understood, and although the preferred embodiment of the invention is as illustrated and described, yet it is to be understood that changes in the details of construction can be had which fall within the scope of the invention as claimed.

What I claim is:

- 10 1. In a bed a foot element comprising a pair of braced, opposed, spaced posts, means arranged between, abutting the inner side faces of and fixedly secured to said posts to provide an open front wardrobe, said posts in proximity to their upper ends overlapping and seating on the top of said means, a vertically movable door for said open front having its upward movement limited by the top of said means, and combined guides and bearings secured to the front of said door.
- 15 2. In a bed a foot element comprising a pair of braced, opposed, spaced posts, means arranged between, abutting the inner side faces of and fixedly secured to said posts to provide an open front wardrobe, said posts in proximity to their upper ends overlapping and seating on the top of said means, a vertically movable door for said open front having its upward movement limited by the top of said means, and combined guides and bearings secured to the front of said door.
- 20 3. In a bed a foot element comprising a pair of braced, opposed, spaced posts, means arranged between, abutting the inner side faces of and fixedly secured to said posts to provide an open front wardrobe, said posts in proximity to their upper ends overlapping and seating on the top of said means, a vertically movable door for said open front having its upward movement limited by the top of said means, and combined guides and bearings secured to the front of said door.

2. In a bed a foot element comprising a pair of braced, opposed, spaced posts, means arranged between, abutting the inner side faces of and fixedly secured to said posts to 25 provide an open front wardrobe, said posts in proximity to their upper ends overlapping and seating on the top of said means, a vertically movable door for said open front having its upward movement limited by the 30 top of said means, combined guides and bearings secured to the front of said means for said door, said door being flexible, and curved means arranged between and secured to said posts and positioned below the bottom 35 of the wardrobe for directing the door when shifted to open position inwardly with respect to the posts.

In testimony whereof, I affix my signature hereto.

SAM FORD.
